ATTY'S

UNITED STATES PATENT OFFICE.

HENRY PAAR, OF CANTON, OHIO, ASSIGNOR OF ONE-THIRD TO CHARLES McGRANAHAN,
OF YOUNGSTOWN, OHIO.

CUSHION-HORSESHOE.

1,338,584.

Specification of Letters Patent. Patented Apr. 27, 1920.

Application filed November 14, 1919. Serial No. 338,052.

To all whom it may concern:

Be it known that I, HENRY PAAR, a citizen of the United States, residing at Canton, in the county of Stark and State of 5 Ohio, have invented a new and useful Cushion-Horseshoe, of which the following is a specification.

This invention relates to horseshoes and more particularly to what might be termed 10 spring-tread or spring-heel shoes, provided with removable cushioned calks, and devised with the object of diminishing concussion to, and preventing the animal accidentally pulling off, the calk in case of 15 meeting with an obstruction.

The objects of the invention are to construct a horseshoe with removable calks whereby all of the advantages of elasticity 20 of tread, and the consequent avoidance of concussion due to hard pavements or roads and the accidental displacement of the calk are obtained, without disadvantage as to the durability of the shoe or injurious effects 25 upon the animal's hoof; and the invention consists in providing the shoe with a pair of removable cushion calks provided with removable and compressible cushions, which can be readily applied to horseshoes now in general use.

30 Further objects are the provision of a removable and replaceable cushion calk for horseshoes which is simple, strong and durable in construction, efficient in use, easily and readily applied to the heel portion of a 35 usual construction of horseshoe, and inexpensive to manufacture.

With these objects in view, the invention consists in the novel construction and arrangement of parts hereinafter described, 40 illustrated in the accompanying drawings, and particularly pointed out in the appended claims, it being understood that various changes in the form, proportions, size, and minor details of construction may 45 be made within the scope of the appended claims, without departing from the spirit or sacrificing any of the advantages of the invention.

Figure 1 is a bottom plan view of a 50 horseshoe embodying the invention;

Fig. 2 is a longitudinal sectional view through the horseshoe;

Fig. 3 is an enlarged longitudinal sectional view through the cushioned calk;

Fig. 4 is a detail perspective view of the 55 calk; and

Fig. 5 is a similar view of the cushion.

A practical embodiment of the invention is disclosed in the accompanying drawings, forming a part of this specification, in 60 which similar numerals of reference indicate corresponding parts throughout the several views.

The shoe is indicated by the numeral 1, and may be of any usual and well-known 65 construction, preferably provided at the toe portion with the integral calk 2. A pair of apertures 3, 3^a is located through each heel portion of the shoe, these apertures being spaced longitudinally upon the shoe as 70 shown and extending vertically through the shoe. With the exception of the provisions of these apertures the shoe is of known construction and is not otherwise changed except that it is provided with the tapped 75 bores 4, one of said bores being provided in each heel portion.

A cushion 5 of rubber or other resilient or elastic material is mounted upon the 80 tread portion of each heel of the shoe, constituting a compressible cushion adapted to diminish concussion upon the animal when the shoe is worn and providing an elastic tread. The cushion is provided with the vertical end grooves 6 adapted to aline 85 with the apertures 3, 3^a, and with a boss 7 provided with a vertical aperture 8 adapted to aline with the tapped bore 4.

A calk 9 is mounted against each of the 90 cushions 5 and provided with the spaced 95 studs 10, 10^a arranged to be accommodated within the grooves 6 and to be slidably received within the apertures 3, 3^a respectively. Each calk is preferably provided upon its inner face with a vertical depression 11 and with an ear 12 at the lower extremity of said depression, said ear having a countersunk aperture 13 therein registering with the aperture 8 in the cushion and arranged to seat the head of the screw 14 100 which is located through the aperture 8 in the cushion and engages the tapped bore 4 in the shoe.

The studs 10, 10^a play in the apertures 3, 3^a in the heels of the shoe while the screw 105 14 retains the calk upon the shoe and prevents the animal from accidentally pulling or knocking off the calk. This screw limits

outward movement of the calk with reference to the shoe, obviating any lost motion, but the inward movement of the calk is limited only by the compression of the 5 cushion 5, a resilient or elastic tread being thus assured and the concussion to the animal being appreciably diminished.

The lower or tread face of the calk is preferably of greater height at its rear end 10 and tapered slightly forward, and is generally provided with the serrated tread face 15 to aid the animal in traveling over icy or slippery roads or pavings.

From the foregoing description it will 15 be evident that a simple and efficient cushioned calk is produced which may be quickly and readily applied to the shoe, means being provided for preventing the accidental displacement of the calk by the animal. It 20 should also be noted that the calk is applicable to any usual construction of shoe, this in itself being a material advantage as no special form of shoe is necessary in carrying out the invention. Furthermore it will 25 be evident that the elasticity of the tread obtained by the construction of shoe above described has the effect of not only diminishing concussion, but of increasing the durability of the shoe, and the cushions be- 30 sides affording elasticity of tread act also as insulators to prevent the transmission to

the hoof of the heat generated by friction or acquired by contact with the hot pavements or roads.

I claim:

1. A horseshoe having each of its heels provided with a pair of spaced apertures, a cushion mounted against each heel between said apertures and having vertical grooves in its ends registering with the 40 apertures, a calk engaging each cushion, studs upon the calk engaging the grooves in the cushion and extending into the apertures, an ear upon the calk, and a screw located through the ear and through the shoe. 45

2. A horseshoe having each of its heels provided with a pair of spaced apertures, a cushion mounted against each heel between the apertures and having vertical grooves in its ends registering with the apertures, a 50 boss upon the cushion provided with a vertical bore, a calk engaging each cushion, studs upon the calk engaging the grooves and extending into the apertures, a perforated ear upon the calk registering with the 55 boss on the cushion, and a screw located through said ear and boss and through the shoe.

In testimony that I claim the above I have hereunto subscribed my name.

HENRY PAAR.
